UNITED STATES PATENT OFFICE.

JOSEPH D. KILGORE, OF HOMESTEAD, PENNSYLVANIA.

TOY CANNON.

1,068,667.

Specification of Letters Patent. Patented July 29, 1913.

Application filed November 13, 1912. Serial No. 731,230.

To all whom it may concern:

Be it known that I, JOSEPH D. KILGORE, a citizen of the United States, residing at Homestead, in the county of Allegheny and State of Pennsylvania, have invented 5 and State of Pennsylvania, have invented new and useful Improvements in Toy Cannons, of which the following is a specification.

This invention relates to a toy cannon 10 containing mechanism for exploding what are known as paper caps; and has for its object to provide a simple, harmless and attractive toy of this type containing suitable mechanism for successively moving into 15 firing position and exploding by the same operation small charges of fulminate mounted at regular intervals on a long strip of paper, the whole forming a repeating cannon which may be actuated equally well by 20 hand or foot.

With this and other objects in view, the invention consists of the novel construction, combination and arrangement of parts hereinafter described and claimed, and illustrated in the accompanying drawings, in which:—

Figure 1 is a side elevation of the toy cannon complete. Fig. 2 is a top plan view of the same. Fig. 3 is an elevation with one of 30 the sides removed. Fig. 4 is a similar view with the firing mechanism in a different position. Fig. 5 is a sectional detail view taken on the line 5—5 of Fig. 3, looking downward. Figs. 6 and 7 are perspective 35 views of actuating dogs or pawls forming a part of the invention. Figs. 8 and 9 are views of blanks from which the respective pawls or dogs are made.

The casing of the toy comprises a hollow 40 shell made in imitation of the shape of a gun *a* and its mount *b*, said shell being formed of two similar halves *A*, *B*, joined together in the vertical longitudinal center of the toy by means of a transverse pin 10 45 riveted or otherwise secured on the outside of the mount. If desired, a second pin indicated at 10^a by dotted lines may be used to further connect the two parts of the casing. The halves or sections *A*, *B*, of the 50 casing are preferably made of cast metal, the meeting edges of which are notched to

form slots 11 and 12 when the sections are joined together for the entrance and exit of a continuous fulminate strip *C* into and from a chamber 13 formed by the hollow 55 mount *b*. At the rear of the bore 14 of the cannon is a partition 15 forming a firing abutment, said partition being continuous with the front 16 of the mount *b* which serves in the present instance as a feeding 60 wall for the fulminate strip. The slot 11 is formed through this wall 16, as shown in Fig. 3. The partition or firing abutment 15 may be cast partly on each section or half, *A*, *B*, of the casing, or if desired 65 wholly on one section but made sufficiently large to project into the other section when the two are joined together to form the casing. In the latter case the firing face of the abutment will be unbroken and perfectly 70 smooth.

Within the chamber 13 is a hammer 17 made preferably of cast metal with pintles 18 integral therewith that are mounted pivotally in holes 19 formed in the sections 75 *A*, *B*. The hammer 17 has a head 20 on its upper end arranged to strike against the abutment and explode the fulminate, while on the opposite side of the axis of the pintles 18 are two spaced lips 21 and 22 between .80 which is an angular projection 23, the use of which parts will be described later.

Below the hammer 17 is an actuating lever 24 pivotally mounted intermediate its ends on the pin 10, one end of which lever 85 projects outwardly through a slot 25 in the rear of the wall of the mount *b* and is provided with an enlargement 26 on which the hand or foot is placed when it is desired to fire the cannon. The inner end of the lever 90 24 has a stud 27 projecting from one side, and a similar stud 28 projecting from the opposite side to form pivots for two pawls or dogs 29 and 30. The lever 24 has also a lug 31 near the stud 28 over which lug 95 rests one end of a curved main spring 32, its opposite end being carried upward to bear against the lip 22 on the hammer for actuating said hammer.

The pawls or dogs 29 and 30 are each 100 made, preferably and for the sake of economy, of sheet metal blanks similar to Figs.

8 and 9, stamped from the metal and afterward bent into shape. The dog 29 is made from a blank similar to *d*, Fig. 9, having an enlargement 33 at one end perforated at 34 to fit over the stud 27 on the lever 24. The upper end of the dog 29 is provided with a plate 35 extending at a right angle thereto, designed to grip between itself and the feeding wall 16, the fulminate strip C 10 and feed the same upwardly to the hammer 17. The plate 35 is formed by bending the part *e* projecting latterly from the blank *d* at a right angle to said blank. The dog 29 has also a retaining finger 36 below 15 the plate 35 formed by bending the lug *f*, Fig. 9, into a half circle.

The pawl or dog 30 has an enlargement 37 similar to that of 33 on the dog 29, and an opening 38 therethrough for the stud 28 carried by the lever 24. A plate 39 projects at a right angle to the dog 30 from its upper end for engaging the lip 21 on the hammer and retracting same when the outer end of the lever 24 is depressed. Extending 25 downward from the enlargement 37 is a finger 40 having a turned in portion 40^a perpendicularly thereto through which is formed a hole 40^b. The dog 30 and its accompanying parts is made from a blank *g*, Fig. 8, having a projection *h* which when bent forms the plate 39, and an extension *i* which forms the finger 40 and its bent portion 40^a. A spring 41 holds the dog or pawl 29 against the feeding wall and also 35 the dog 30 in engagement with the lip 21. This spring has one of its ends connected to the dog 30 by passing through the hole 40^b in the bent end of the finger 40, the opposite end of said spring bearing against the retaining finger 36 on the dog 29, the spring 40 being curved around and under the dog 29 as shown.

To operate the invention, a fulminate strip is passed through the slot 11, up the 45 feeding wall 16 and firing abutment 15 to the hammer, the lug or plate 35 pressing against said strip as shown in Fig. 3. If now the hand or foot be placed upon the outer end of the lever 24 and pressed downwardly the inner end of said lever rising, 50 lifts the dogs 29 and 30 as is evident, the dog 29 feeding upward the fulminate strip, while the dog 30 engaging lip 21 of the hammer retracts the same thereby compressing the main spring 32. When the hammer has been retracted sufficiently far to deliver 55 a blow against the firing abutment with force enough to explode the fulminate, the dog or pawl 30 is disengaged from the lip 21 so that the hammer may fall. This is done by the angular projection 23 on the hammer which moves in a forward direction as the upper end of the hammer is re-

tracted and when the hammer reaches the point described, the projection 23 will be in 65 contact with the dog 30 and further movement of the lever 24 causes said projection 23 to push the dog out of engagement with the lip 21 and release the hammer which falls upon the fulminate strip and produces 70 the explosion. Pressure on the lever 24 is now removed to permit the lever to return to normal position under the influence of the main spring 32. This movement of the lever lowers the dogs 29 and 30 sufficiently 75 to permit the dog 29 engaging the fulminate strip to feed another charge to the firing abutment, and the dog 30 to spring past the outer edge of the lip 21 into engagement therewith. The toy is now in position 80 for a second firing and this action may be kept up as long as the fulminate strips last.

Having thus described my invention what I claim is:

1. A toy cannon formed with a chambered 85 mount, a cap-strip feeding wall and a firing abutment contained therein at the front of the chamber, a hammer pivoted within the chamber for exploding the caps on the strip, an actuating lever pivoted within the 90 chamber and projecting at one end rearwardly through the mount in position to be actuated by the hand or foot, a feeding dog and a hammer retracting dog pivoted on the inner end of the actuating lever, a main 95 spring for the hammer and the actuating lever, and a second spring for the two dogs.

2. A toy cannon formed with a chambered 100 mount, the front side of which chamber forms a cap-strip feeding wall and a firing abutment continuous with said wall, an inlet slot for the cap-strip formed through said side below the cannon, and an outlet slot for said strip through the top above the firing abutment, a hammer, an actuating lever, 105 a cap-strip feeding dog and a hammer retracting dog pivoted on opposite sides of the inner end of the actuating lever, a spring connected at each end respectively to one of the dogs for holding them to their work, and 110 a main spring connected to the hammer and to the actuating lever.

3. A toy cannon formed with a chambered 115 mount, said chamber containing a firing abutment and a cap-strip feeding wall, a hammer, an actuating lever projecting at one end through the rear wall of the mount, a cap-strip feeding dog of sheet metal pivoted on one side of the opposite end of said 120 lever with an engaging plate on its free end formed by bending a portion of said dog into position to bear against the feeding wall and advance the cap-strip, and with a retaining finger below said plate, and a hammer retracting dog also of sheet metal 125 pivoted on the opposite side of the inner

end of the actuating lever with a similar bent plate at its free end to engage the dog and a bent finger on the opposite side of its pivotal axis, and a spring connected to said bent finger and to the retracting finger of the feeding dog.

In testimony whereof I have hereunto set

my hand in presence of two subscribing witnesses.

JOSEPH D. KILGORE.
